UNITED STATES PATENT OFFICE.

CLAUDE G. MINER, OF BERKELEY, CALIFORNIA.

ELECTRIC FURNACE.

1,232,362.

Specification of Letters Patent.

Patented July 3, 1917.

Application filed February 17, 1917. Serial No. 149,248.

To all whom it may concern:

Be it known that I, CLAUDE G. MINER, a citizen of the United States, residing at Berkeley, in the county of Alameda and State of California, have invented new and useful Improvements in Electric Furnaces, of which the following is a specification.

This invention relates to improvements in electric furnaces.

The primary object of this invention is to provide a type of an electric furnace especially suitable for laboratory and scientific work on a small scale.

Another object is to provide a furnace which is adapted to the use of inexperienced operators, and more especially, capable of being readily altered from the arc to the resister type by such operators.

A third object is to combine in such a furnace means by which rapid and intense heating is secured, together with economy of operation.

With these and other objects in view, which will appear upon perusal of the accompanying description and claims, and an examination of the drawings herewith, I have embodied my invention in the form shown and described below.

In the drawings,

Figure 1 is a sectional side elevation of the furnace.

Fig. 2 is a sectional plan view taken at a point midway of the reaction chamber of the furnace.

Fig. 3 illustrates a cover block provided for the crucible of the furnace when the resister principle is utilized.

Fig. 4 is a sectional view of the cover block.

Referring now to the drawings in detail, 1 designates standards serving as a support for the outer wall 2 of the furnace which may be constructed of firebrick or other suitable refractory material. Inside wall 2, 5 but separated therefrom by cavities 3, filled with heat insulating material, is a mass of refractory material 4 wherein the reaction chamber 5 is situated, said reaction chamber being in form similar to two opposed paraboloids having the major axis thereof extending vertically. The upper portion of

reaction chamber 5 is provided with an observation tube extending through the outer portions of the furnace, and similar tubes, 14 and 15, for the escape or admission of 55 gases. Horizontally placed midway between the top and bottom of said reaction chamber is a support 6 for the crucible 7. The purpose of giving to chamber 5 a paraboloid form is to secure greater concentration of heat upon the crucible 7, which is 60 preferably placed in the principal foci of the paraboloids.

Another advantage of this shape of chamber arises from the fact that the cubic capacity is thereby reduced, resulting in economy of electrical consumption.

Economical operation is furthermore assisted by the cavity 3 filled with heat insulating material; which is preferably composed of infusorial earth, this material being 70 an excellent non-conductor of heat.

Downwardly extending through walls 2 and 4 into the combustion chamber 5 is an electrode 8, of carbon or other suitable material, said electrode being provided with a support and means of adjustment 9 secured to the outer wall of the furnace, and being further provided with suitable means of electric connection. A second electrode 10 80 which may or may not be somewhat larger than electrode 8 and provided with a similar means of support and adjustment 11, extends upwardly through walls 2 and 4 into the reaction chamber 5, and is similarly 85 provided with means of electric connection. A third electrode 12 extends laterally through walls 2 and 4, terminating at a point slightly within chamber 5 and establishing connection with the crucible support 90 6. This crucible support when for use in connection with the series arc principle is made of refractory but non-conducting material, the crucible in this case being of carbon or other refractory conducting material 95 such as commonly is used in the art.

When operating the furnace upon the arc principle, the electrode 10 is raised by means of an adjustment 11 until it establishes connection with crucible 7, electrode 8 being 100 then lowered until it contacts with the upper portion of crucible 7, and quickly with-

- drawn, thereby creating an arc. If desired, electrode 10 may now be drawn out of contact with crucible 7, producing a second arc, resulting in extremely intense and rapid heating of the contents of the crucible 7. This method of operation utilizes in series connection the two arcs, but as sufficient voltage to operate two arcs in series may not always be available, a third connection 12 10 is provided by means whereof the two arcs are operated in parallel. To effect this the support 6 is removed from chamber 5, a similar support composed, however, of refractory conducting material such as commonly used in the art, for instance, carbon, being substituted. Electrodes 8 and 10 are then connected to one lead from the source of current supply, terminal 12 being connected to the other lead.
- 20 As it is often desirable to utilize the resistance principle of operation in such a furnace, means of readily altering the furnace to effect this are provided, these means consisting of a conducting refractory support 25 similar to that used when operating with arcs in parallel, but used in this connection with the non-conducting crucible 7 of refractory material. A suitable cover-block 13 of refractory conducting material is provided for crucible 7. The electrode 10 is brought near crucible 7 by means of the adjustment 11, and the lower portion of the reaction chamber is filled with carbon, graphite, or other suitable material as commonly used in the art, to the support 6; and the operation of the furnace is started by lowering electrode 8 until it establishes connection with the cover 13 of crucible 7. When used as a resister furnace, electrodes 40 8 and 10 are connected in series.
- The above description and drawings are not to be interpreted as in any way limiting the scope of this invention, being merely intended to illustrate one of many possible 45 embodiments thereof.
- What I claim is:
1. In an electric furnace, a body formed with a cavity having the shape of two opposed paraboloids, means in said cavity for maintaining a substance to be heated in the principal foci of said paraboloids, said means adapted to serve as a center electrode for two arcs in series.
  2. In an electric furnace, a body having outer and inner spaced walls of refractory material and having the space between said walls filled with heat insulating material; said body formed interiorly of said inner wall with a cavity having the shape of two 55 opposed paraboloids.
  3. In an electric furnace, outer and inner spaced walls and heat insulating material in the space between said walls; said furnace
- formed interiorly of said inner wall with a reaction chamber having the shape of two opposed paraboloids; and means whereby said furnace may be used as an arc furnace and as a resister furnace interchangeably.
4. In an electric furnace, outer and inner spaced walls and heat insulating material in the space between said walls; said furnace formed interiorly of said inner wall with a reaction chamber having the shape of two opposed paraboloids; and a crucible composed of conducting material in the principal foci of said paraboloids, said crucible constituting a center electrode for two arcs in series.
5. In an electric furnace, outer and inner spaced walls and heat insulating material in the space between said walls; said furnace formed interiorly of said inner wall with a reaction chamber having the shape of two opposed paraboloids; and a crucible in the principal foci of said paraboloids, said crucible constituting a common electrode for two arcs in parallel.
6. In an electric furnace, outer and inner spaced walls of refractory material, heat insulating material in the space between said walls; said furnace formed interiorly of said inner wall with a reaction chamber in the form of two opposed paraboloids; a crucible in the principal foci of said paraboloids, said crucible adapted to coöperate with means constituting an arc heating device; a second crucible adapted to be substituted for the first mentioned crucible, said second mentioned crucible further adapted to coöperate with means constituting a resistance heating device.
7. In an electric furnace, outer and inner spaced walls and heat insulating material in the space between said walls; an arc heating means in said furnace and a resistance heating means adapted to be substituted for said arc heating means.
8. In an electric furnace, a body having outer and inner spaced walls and having the space between said walls filled with heat insulating material; said body formed interiorly of said inner wall with a cavity, said cavity having the shape of two opposed paraboloids.
9. In an electric furnace, a body formed with a cavity having the shape of two opposed paraboloids, and means in said cavity for maintaining a substance to be heated in the principal foci of said paraboloids, said means adapted to serve as a common electrode for two arcs in parallel.
10. In an electric furnace, a body having outer and inner spaced walls and having the space between said walls filled with heat insulating material; said body formed interiorly of said inner wall with a cavity, and a

crucible in said cavity, said crucible constituting a common electrode for two arcs in parallel.

11. In an electric furnace, a body having outer and inner spaced walls and having the space between said walls filled with heat insulating material; said body formed interi-

orly of said inner wall with a cavity, and a crucible in said cavity, said crucible constituting a common electrode for two arcs in series.

In testimony whereof I affix my signature.

CLAUDE G. MINER.
